UNITED STATES PATENT OFFICE.

WILLIAM F. LAMBERT, OF MILLBRAE, CALIFORNIA.

DESIGN FOR A PICTURE-FRAME.

SPECIFICATION forming part of Design No. 23,284, dated May 22, 1894.

Application filed September 25, 1893. Serial No. 486,488. Term of patent 3½ years.

To all whom it may concern:

Be it known that I, WILLIAM F. LAMBERT, a citizen of the United States, residing at Millbrae, county of San Mateo, State of California, have invented and produced a new and original Design for a Picture-Frame, of which the following is a specification, reference being had to the accompanying drawings, forming a part thereof.

10 The drawings represent the outside and inside views of the design for a picture frame when open, showing the design as it appears upon the frame.

Figure 1, is a view of the picture frame as 15 open showing my design upon the upper side. Fig. 2, is a view of the inside of said frame as open showing my design on under side of upper frame piece.

The leading feature of my design consists 20 in a picture frame, as herein illustrated. The outside portion of said frame is narrow and thick,—the body part consisting of a pencil shaped piece inclosed by and sunken below said narrow and thick part of the frame in 25 which panel pieces are the blank spaces for card and pictures upon the outside and inside of said frame.

A. represents the open design folding picture frame; B. the blank card space on front 30 side of upper frame; D. the blank picture

space on inside of upper frame; E. E. the blank spaces on inside of upper frame; a. a vine design running on the narrow raised border or thick part of frame inside and outside; b. a bead border design surrounding 35 the inside of thick frame part above the sides of panel part; c. cornucopia design with fruit, and scroll work on the outside of upper frame part; d. medallion design representing a landscape with tree trunk and a bear crossing over 40 it, said medallion having a vine representation at right side and surrounding it; e. e. border to card space showing circular shaped design dotted near the edge and having small leaf representation near central part; g. chain 45 design about oval shaped blank space on inside upper panel; h. h. fern design on right hand upper corner and left hand lower corner of said panel; l palm leaf design in left hand upper corner, and m. a century plant 50 design in right hand lower corner of said inside upper frame part.

What I claim, and desire to secure by Letters Patent of the United States, is—

The design for a picture frame as herein 55 described and shown.

WILLIAM F. LAMBERT.
